MACHINE FOR USE IN APPLYING PRESSURE
TO SHOE BOTTOMS

Francis J. Better, Beverly, Mass., assignor to
United Shoe Machinery Corporation, Borough
of Flemington, N. J., a corporation of New
Jersey

Application July 16, 1940, Serial No. 345,747

15 Claims. (Cl. 12—33)

This invention relates to machines for use in applying pressure to shoe bottoms and more particularly to means for relatively positioning a shoe and a plurality of shoe bottom members prior to the application of pressure thereto.

One type of women's shoe that has recently been popularized is the so-called platform sole shoe. This type of shoe has a thick midsole positioned between the shoe and the outsole, this midsole being known as a platform. In order properly to join the shoe, the midsole and the outsole together by cement by applying pressure between the parts, it is necessary that the parts be accurately positioned relative to one another prior to the application of pressure thereto. It is an object of this invention therefore to provide improved means for relatively positioning a plurality of shoe parts prior to the application of pressure between the parts.

In the illustrated embodiment of the invention the positioning means are incorporated in a machine of the type illustrated in Letters Patent of the United States 2,047,185, granted June 14, 1936, on an application of M. H. Ballard et al. In accordance with one feature of the invention, feelers are provided for finding and holding the forepart of a sole placed on a pressure-receiving pad and associated with these feelers are gages arranged to position the forepart of a midsole relative to the outsole and position the forepart of a shoe relative to the midsole. A pin adjustable longitudinally of the pad is arranged to engage a hole punched in the heel seat of the outsole to position the heel end of the outsole widthwise of the pad, this pin being carried by a resilient tongue arranged to be located between the outsole and a midsole or platform sole placed thereon. Gages are provided for positioning the heel end of the midsole relative to the outsole and other gages are provided for positioning the heel end of the shoe relative to the midsole. The various gages are arranged to be adjusted to provide the proper alinement and overhang of the various parts relative to one another.

These and other features of the invention will be described in detail in the specification and illustrated in the drawings, in which

Fig. 1 is a side elevation of a pad box with which is associated one form of positioning means for the forepart of a shoe, a midsole and an outsole and one form of positioning means for the heel ends of these members, the heel end positioning means being shown in section;

Fig. 2 is a plan view of the pad box and the positioning means;

Fig. 3 is a perspective view of one of the positioning devices for the forepart; and

Fig. 4 is an end elevation of the positioning device of Fig. 3.

52 A pad box 10 which may be similar to that illustrated in the Ballard et al. patent referred to above is provided with a pad 12 for receiving the shoe parts for the application of pressure therebetween upon downward movements of a toe pad 14 and a heel abutment 16, these members being arranged to move downwardly after the shoe and shoe bottom members have been properly positioned on the pad.

15 The positioning means for the heel end of the shoe and the shoe bottom members are mounted on a support 18 pivoted at 20 to a support 22 adjustably secured by a screw 24 to an arm 26. The screw 24 passes through a slot in the arm 26 to provide for lengthwise adjustment of the support 18 relative to the pad. The arm 26 is carried by a vertical slide 28 and is urged upwardly to the position illustrated in Fig. 1 by a spring 30

20 acting between the slide and a bracket 32 rigid with the pad box 10. The support 18 is maintained in the desired position of adjustment relative to the support 22 by a screw 34 threaded through the support 22, the adjacent portion of the support 18 being maintained in engagement with the screw by a compression spring 36.

25 30 For locating the heel end of an outsole transversely of the pad, a sole-receiving pin 38 (Fig. 2), arranged to be engaged with a hole punched in the heel seat of an outsole, is carried by a re-

35 sili ent tongue 40 which is in turn secured to an arm 42 pivoted at 44 to a slide 46 arranged for movement lengthwise of the pad box in the support 18. A spring pressed detent 47 (Fig. 2) engaging an elongated recess in the slide 46 limits the sliding movement thereof. A spring 48 se-

40 cured to the slide 46 and to the arm 42 urges the arm downwardly to maintain the tongue 40 in engagement with a sole placed on the pad. In order to raise the tongue 40 and pin 38 away from the pad box to permit the insertion of a sole therebetween, the arm 42 is provided with a handle 50 by which the arm 42 may be moved about the pivot 44 against the tension of the spring 48.

45 Also carried by the support 18 is a pair of arms 52 and 54 (Fig. 2) pivoted about horizontal axes by pins 55 to arms 56 which are arranged for equal and opposite movements. These arms are arranged to be moved toward each other by a compression spring 60 acting on a slide 58 in a

50 55 manner fully disclosed in Letters Patent of the

United States 2,005,755, granted June 25, 1935, on an application filed in my name. The arms 52 and 54 carry at their inner ends gages 62 and 64 arranged to engage a midsole placed on the outsole to position the heel end of the midsole relatively thereto. The gage 62 is pivotally connected to the arm 52 by means of a pivot pin 66, the gage 62 having a rearward extension 68 through which is threaded a screw 70 arranged to engage the adjacent surface of the arm 52 to [10] adjustably position the gage relative to the arm. A spring 72 acts between the gage 62 and the arm 52 to maintain the screw 70 in engagement with the arm 52. This adjustment of the gage 62 relatively to the arm 52 provides for lateral [15] adjustment of the midsole relatively to the outsole.

The gages 62 and 64 are maintained in the proper heightwise positions relative to the pad by means of stops 76 (Fig. 1) arranged to engage the pad 12, these stops being formed at the lower ends of screws 78 passing through the arms 52 and 54. Adjustment of the screws 78 relatively to the arms causes vertical adjustment of the arms relatively to the arms 56 thereby permitting heightwise adjustment of the midsole gages relatively to the pad.

In order to position the heel end of a shoe laterally relatively to the midsole, shoe gages 80 are provided, these gages being formed at the ends of arms 82 carried by the support 18 and arranged for equal and opposite movements by a tension spring 84 acting upon a slide 86, the slide being connected to the arms 82 in the manner shown in my earlier patent. The lateral position of the shoe gages 80 relative to the midsole gages may be adjusted by rotation of an adjusting arm 88 as explained in my earlier patent and the heightwise position of these gages may be varied by adjusting the position of the support 18 by the screw 34.

The gages thus far described determine the relative positions of the heel ends of the outsole, the midsole and the shoe widthwise of the pad, the lengthwise positions of these members being determined by gages to be described. Gage assemblies 90 mounted on the outer ends of arms 92 are provided for engaging the foreparts of the shoe, the midsole and the outsole at the opposite sides thereof. The gage assemblies 90 are arranged to be moved inwardly toward one another by swinging movements imparted to the arms 92 upon treading of the machine by the operator, as described in the Ballard et al. patent, after the sole has been placed on the pad.

One of the gage assemblies is illustrated in detail in Figs. 3 and 4 and comprises a gage or feeler member 94 extending inwardly of the pad box at the lower end of an arm 96 depending from the arm 92. The outer end of the arm 92 is provided with ways 98 and 100 for slides 102 and 104 respectively. The slide 102 is formed with a downwardly extending arm 106 the lower end of which is provided with a gage 108 extending above and substantially co-extensive with the feeler 94. The slide 102 is held in adjusted position relative to the arm 92 by means of a screw 110 threaded through an upwardly extending boss 112 secured to the slide 102. The screw 110 is provided with collars 114 engaging opposite sides of a pin 116 (Fig. 4) secured to the arm 92 to prevent axial movement of the screw 110 whereby rotative movement thereof causes the slide 102 to be moved to adjust the gage 108 relatively to the feeler 94. The gage 108 is ar-

5 ranged to engage the midsole M, as indicated in Fig. 4, whereby the position of the midsole relative to the outsole O is determined by adjustment of the gage 108 relative to the feeler 94 thereby determining the amount of the overhang of the outsole relative to the midsole, if any.

In order to determine the position of the forepart of a shoe S relative to the midsole, a gage 120 extending above the midsole gage 108 is connected to the slide 104. This slide is maintained in the desired position of adjustment in the same way as the slide 102 and the position of the gage 120 relative to the midsole gage 108 thus determines the position of the forepart of the shoe relative to the midsole.

Additional feelers 122 (Fig. 2) arranged to engage the opposite sides of the outsole near the ball line are carried at the outer ends of arms 124 which are arranged to be swung inwardly upon treading of the machine, as illustrated in the Ballard et al. patent, and associated with these feelers are gages 126 arranged to determine the lateral position of the outsole relatively to the midsole in the vicinity of the ball line.

Before placing an outsole on the pad box, the forepart gages and feelers carried by the arms 92 and 124 are separated as are the midsole gages 62 and 64 and the shoe gages 80 at the opposite end of the pad box. The midsole gages 62 and 64 are maintained in open position against the force exerted by the compression spring 60 by means of a bell crank lever 128, the end of which carries a roll 130 arranged to engage the slide 58 when the bell crank lever is moved about its pivot in a clockwise direction from the position illustrated in Fig. 2. The shoe gages 80 are maintained in spaced-apart position against the force exerted by the tension spring 84 by a link 132 connected at one end to the slide 86 and pivotally connected at its other end to mechanism operated upon swinging the toe and heel abutments 14 and 16 into pressure-applying position to permit movement of the slide 86 by the spring 84 to move the shoe gages toward one another as explained in my aforementioned patent.

The outsole is placed upon the pad by the operator, the position of the heel part of the outsole widthwise of the pad box being determined by the pin 38 carried by the tongue 40, the tongue being swung upwardly before placing the sole on the pad by depression of the handle 50. The position of the sole lengthwise of the pad is at the discretion of the operator and the heel-engaging pin 38 is adjustable longitudinally of the pad box since it is carried by the slide 46. Upon placing the sole on the pad and engaging the hole in the heel end thereof by the pin 38, the operator treads the machine which causes a bell crank lever 140 pivoted at 142 to the pad box to be swung, thereby operating a link 144 which permits the arms 92 to swing toward one another until the feelers 94 find the opposite sides of the forepart of the outsole whereupon movement of these arms will stop. Likewise the arms 124 move inwardly until the feelers 122 carried thereby find the opposite sides of the outsole in the vicinity of the ball line. At the same time, a link 146 is operated to rotate the bell crank lever 128 in a counterclockwise direction whereby the compression spring 60 is effective to move the midsole gages 62 and 64 inwardly. At this time, since the midsole has not been placed on the outsole, these gages may move inwardly of the outsole, the stops 76 which space these gages above the pad box being permitted by reason of their

curvature to ride over the edge of the outsole. In order to move these gages apart during the pacing of the midsole on the outsole, a handle 150 connected to the slide 58 is provided whereby the operator may move the slide against the force of the spring 60 to open up these gages thereby permitting the heel end of the midsole to be placed on the outsole.

The outsole is now held in place by the forepart feelers and the heel-engaging pin 38 and is ready to have the midsole placed thereon. The operator places the midsole on the outsole with the toe end of the midsole in engagement with the gages 108, the lateral position of the midsole relative to the outsole in the vicinity of the ball line being determined by the gages 126. The gages 62 and 64 for the heel end of the midsole will now be moved apart by the handle 150 whereupon the heel end of the midsole is placed on the outsole and the handle 150 released so that the heel end of the midsole will be moved into proper position relative to the outsole. The shoe is now placed on the midsole, its position at the toe end being determined by the shoe gages 120 and at the ball line by the gages 126. The toe and heel abutments 14 and 16 are now moved into register with the shoe, this action permitting movement of the shoe gages inwardly toward one another under the force exerted by the spring 84 as described in my earlier patent, thus positioning the heel end of a shoe in proper register relative to the midsole.

It will thus be seen that three parts of a shoe, such as an upper, a midsole and outsole, may be readily positioned in a predetermined manner relatively to one another by means of the novel arrangement of the various gages which are relatively adjustable to provide for varying amounts of overhang of the various parts. The various gages used to effect the proper alinement of the shoe parts to be secured together may be readily attached to a machine of the type illustrated in the Ballard et al. patent although their use is not limited to a machine of this type.

Having thus described my invention, what I claim as new and desire to secure by Letters Patent of the United States is:

1. A pad box for use in applying pressure to shoe bottoms having in combination a sole receiving pad, means for holding the forepart of an outsole placed on the pad, means for positioning the forepart of a midsole relatively to the forepart of the outsole, and additional means for positioning the forepart of a shoe relative to the outsole and the midsole.

2. A pad box for use in applying pressure to shoe bottoms having in combination a sole receiving pad, means for holding the forepart of an outsole placed on the pad, means for positioning the forepart of a midsole relatively to the forepart of the outsole, additional means for positioning the forepart of a shoe relative to the outsole and the midsole, and means for adjusting said holding means and said positioning means relative to one another.

3. A pad box for use in applying pressure to shoe bottoms having in combination a sole receiving pad, means for finding the forepart of an outsole placed on the pad, means for positioning the forepart of a midsole relatively to the forepart of the outsole, additional means for positioning the forepart of a shoe relative to the outsole and the midsole, and means for adjusting each of said positioning means relatively to one another.

4. A pad box for use in applying pressure to shoe bottoms having in combination a sole receiving pad, means for finding the forepart of an outsole placed on the pad, means for positioning the forepart of a midsole relatively to the forepart of the outsole, additional means for positioning the forepart of a shoe relatively to the outsole and the midsole, and means for individually adjusting each of said positioning means relatively to said finding means.

5. A pad box for use in applying pressure to shoe bottoms having in combination means for finding the forepart of an outsole placed on the pad, means for locating the heel portion of the outsole on the pad, means for positioning the forepart and heel part of a midsole relatively to the outsole, and means for positioning the forepart and heel part of an upper relatively to the midsole and the outsole.

6. A pad box for use in applying pressure to shoe bottoms having in combination a sole receiving pad, gage means for locating an outsole on the pad, means for positioning a midsole relatively to the outsole, additional means for positioning a shoe relatively to the outsole and the midsole, and means for adjusting the heightwise position of the midsole positioning means.

7. A pad box for use in applying pressure to shoe bottoms having in combination a sole receiving pad, gage means for holding an outsole on the pad, means for positioning a midsole relatively to the outsole, additional means positioning a shoe relatively to the outsole and the midsole, and means for adjusting the relative heightwise positions of said positioning means.

8. A pad box for use in applying pressure to shoe bottoms having in combination a sole receiving pad, gage means for holding an outsole on the pad, means for positioning a midsole relatively to the outsole, additional means for positioning a shoe relatively to the outsole and the midsole, means pivotally supporting said midsole positioning means for vertical movement and vertically adjustable means carried by said midsole positioning means for engaging the pad whereby the heightwise position thereof may be varied.

9. A pad box for use in applying pressure to shoe bottoms having in combination a sole receiving pad, a pin for engaging a hole in the heel end of an outsole placed on the pad, means for positioning the heel end of a midsole relatively to the outsole, and means for positioning the heel end of a shoe relatively to the midsole and the outsole.

10. A pad box for use in applying pressure to shoe bottoms having in combination a sole receiving pad, a pin for engaging a hole in the heel end of an outsole placed on said pad, a pair of gages arranged to engage opposite sides of a midsole near the heel end thereof when placed on said outsole, and a pair of gages disposed above said midsole gages for positioning the heel end of a shoe placed on the midsole.

11. A pad box for use in applying pressure to shoe bottoms having in combination a sole receiving pad, a pin for engaging a hole in the heel end of an outsole placed on said pad, a pair of gages arranged to engage opposite sides of a midsole near the heel end thereof when placed on said outsole, a pair of gages disposed above said midsole gages for positioning the heel end of a shoe placed on the midsole, and means for varying the relative lateral positions of said midsole and shoe gages.

12. A pad box for use in applying pressure to

shoe bottoms having in combination a sole receiving pad, a gage for holding an outsole placed on the pad, a gage for positioning a midsole relative to the outsole, and a gage for positioning an upper relative to the midsole and outsole, said gages being located one above the other in the order named.

13. A pad box for use in applying pressure to shoe bottoms having in combination a sole receiving pad, a gage for holding an outsole placed on the pad, a gage for positioning a midsole relative to the outsole, a gage for positioning an upper relative to the midsole and outsole, said gages being located one above the other in the order named, and means for adjusting the relative lateral positions of said gages.

14. A pad box for use in applying pressure to shoe bottoms having in combination a sole receiving pad, a feeler for finding an outsole placed on

the pad, a gage for positioning a midsole relatively to the outsole, a gage for positioning an upper relatively to the midsole and outsole, said gages being located one above the other and above the feeler in the order named, and means for independently adjusting the midsole gage and the shoe gage relatively to the feeler.

15. A pad box for use in applying pressure to shoe bottoms having in combination a sole receiving pad, a feeler for finding an outsole placed on the pad, means for supporting said feeler for lateral movement relative to the pad, a gage carried by said supporting means for lateral adjustment relative to said feeler and arranged to position a midsole relative to the outsole, and a gage carried by said supporting means for lateral adjustment relative to the feeler and arranged to position a shoe relative to the outsole and the midsole.

FRANCIS J. BETTER.
